EDWIN O. BARSTOW AND THOMAS GRISWOLD, JR., OF MIDLAND, MICHIGAN.

METHOD OF SEPARATING VOLATILE CONSTITUENTS.

1,261,005.

Specification of Letters Patent. Patented Apr. 2, 1918.

Original application filed October 9, 1912, Serial No. 724,785. Divided and this application filed December 21, 1914. Serial No. 878,327.

To all whom it may concern:

Be it known that we, EDWIN O. BARSTOW and THOMAS GRISWOLD, Jr., citizens of the United States, and residents of Midland, county of Midland, State of Michigan, have jointly invented a new and useful Improvement in Methods of Separating Volatile Constituents, of which the following is a specification, the principle of the invention 10 being herein explained and the best mode in which we have contemplated applying that principle, so as to distinguish it from other inventions.

The present improved method of separating volatile constituents relates to the removal of such constituents from either liquid or solid materials by means of steam or other condensable vapor, a continuous process of working being preferably employed.

20 Thus the present method finds one field of use in connection with a continuous process of extracting oils and the like, such as shown and described in our co-pending application filed October 9, 1912, Serial 25 No. 724,785, (since issued into Patent No. 1,125,920, dated January 19, 1915) being used both to recover residual solvent left in the spent material and to recover or separate the solvent from the final extract.

30 As exemplified in both the foregoing practical applications of the present method, the material to be treated is caused to pass in an approximately continuous current into, through and out of a contact chamber into 35 which steam or other suitable vapor is introduced in a like continuous current, near or at the point where the material leaves the chamber. By structural means suited to the case, this current of steam is caused to flow 40 in a direction opposite to that of the material and to pass through, mix with or contact with it in the chamber, and to finally issue at a point near or at the entrance of the current of material into the contact chamber.

45 The effect of the contact of such oppositely-moving currents is to vaporize the solvent and in so doing to condense an equivalent of steam. The vaporized solvent mixes and flows on with the remaining uncon- 50 densated steam, while the steam is condensed in contact with the material in raising its temperature and evaporating the volatile constituent and flows back with the non-volatile. The two oppositely-moving cur- 55 rents of material and vapor, therefore, vary

in composition throughout the path of contact. The current of material loses volatile constituents and gains in water of condensation, while the current of vapor gains in volatile constituents and loses in steam. Concurrently with the varying composition of the current of vapor, the vapor temperature will also vary from a high value at point of first contact of the incoming steam with the current of spent material to a low value at 60 the last point of contact of the current of vapor with the incoming current of material. The high value will approximate the temperature of steam at the inlet pressure in the contact chamber and the low value will 65 approach the temperature of the vapor of the volatile constituent at the exit pressure; which latter will in all cases be plainly less than the inlet pressure within the contact chamber. Between these high and low 70 values the temperature of the current of vapor will fall as the proportion of steam therein decreases and the low value will be lowest when the percentage of vapor of volatile constituent is highest.

75 Complete removal of the volatile constituent requires more or less intimate and prolonged contact with the steam, depending on the nature of the material and volatile constituent and the boiling point of the mixture thereof; whereas, economy of steam requires that only enough be used to supply the heat necessary to raise the material to the necessary terminal temperature and to evaporate the volatile constituent at its boiling point.

80 Control of the steam supply in any given case may be based upon periodical tests of the spent material to ascertain the portion, if any, of volatile constituents remaining 85 therein, and by observation of the proportion of water of condensation (excess steam) coming over from the condenser in which the vaporized volatile constituent is recovered. The indications, however, of these 90 periodical tests, or observations of excess condensed steam accompanying the recovered volatile constituent, are far too tardy for practical purposes. In other words, 95 these tests and observations reflect on conditions which may have changed by the time they are made, and hence any such method of control is lacking in sensitiveness. In attempting to overcome the difficulties attendant upon the foregoing method of regu- 100 105 110

lation, we have found that if a thermometer be placed in the mixture of vapor of volatile and steam at some point in the path of the latter's contact with the material, the reading of said thermometer will indicate closely the composition of the vapor at that point, and that consequently variations of such reading will indicate variations in such composition. Hence for any selected point in 10 the path in question there is a critical temperature which, if maintained, will insure the most complete possible removal of volatile with the expenditure of the least possible amount of steam.

15 We accordingly provide means for varying the steam supply to satisfy the indications of a thermometer placed in the path of contact of the current of material and steam at some point after or later than the 20 first point of contact of the two, in such manner as to keep the temperature reading at the selected point constant within narrow limits. To the accomplishment of the foregoing object, the invention, then, consists of the steps hereinafter fully described 25 and particularly pointed out in the claims.

The annexed drawing and the following description set forth in detail certain steps embodying the invention, such disclosed 30 steps constituting, however, but one of various ways in which the principle of the invention may be used.

In said annexed drawing:—

Figure 1 illustrates our present improved 35 method in diagrammatic fashion; while Fig. 2 illustrates one form of a practical apparatus designed for carrying out the invention in connection with the treatment of solid materials.

40 In the illustrative apparatus of Fig. 1, the chamber 1 is of course merely typical, the material whether liquid or solid, flowing as indicated by the line 2 from the inlet 3 near the upper end of the chamber to the 45 outlet 4 near the latter's lower end. Opposed to the current of material is a current of steam 5, which is admitted through inlet pipe 6, near the lower end of the chamber, and passes out, near the latter's upper 50 end, by way of discharge pipe 7. As already explained the quantity of steam thus discharged is desirably kept at a minimum the vaporized volatile constituting the major portion of the vapor that passes off. 55 Such vapor is thereupon condensed, as in a condenser 8, and the volatile thus recovered.

At a point intermediate of the ends of the chamber 1, is placed a thermometer 9 extending within said chamber so as to be 60 affected by the temperature of the commingled steam and vapor therein. Said thermometer obviously serves to indicate temperature at this point and will preferably have a mark 10 indicating what may be 65 termed the critical point for such tempera-

ture, at which, in other words, the desired vaporization of the solvent will be secured with the use of a minimum amount of steam. The supply of the latter is designed to be controlled by a valve 10 in the steam-supply line 6, whereby the operator may regulate the admission of steam in accordance with variations in the temperature of the current of vapor at the point where the thermometer is located, the object being to 70 keep said thermometer at the temperature indicated by the mark 10 at all times.

The apparatus illustrated in Fig. 2 is specifically designed for the treatment of relatively solid material in accordance with the 80 present improved process, such for example as the spent extracted material delivered from an extractor of the kind illustrated in our co-pending application previously referred to. The material from the extractor 85 proper (not shown) is designed to be delivered to the chamber 52 by a conveyer 51, preferably comprising a tube within which revolves a screw of usual form, such tube extending to the upper end of the chamber. 90 The latter is shown as vertically disposed and forms a heater where the solvent remaining in the material is removed by contact with a counter current of steam. The screw of conveyer 51 stops short of the opening in the steamer chamber, so that such opening is closed by a plug of the moist material which serves to prevent the escape of steam or vaporized solvent from the 95 steamer.

100 Within the steamer chamber are arranged a plurality of shelves 53 which open alternately at the center and periphery of the chamber. A central rotatable shaft 54 extends longitudinally of the chamber and 105 carries rakes 55, or like devices, which move over and just above the several shelves, being adapted to turn over the material on said shelves and to gradually move the same in a spirally inward or outward direction, 110 as the case may be, depending upon whether the shelf opens centrally or at its periphery. The entering material is thus spread out and broken up on the upper shelf, fed gradually across it, dropped onto the next 115 lower shelf and so on from shelf to shelf until such material reaches the bottom of the chamber where it is received by the inner end of another screw conveyer 56 that delivers it without the apparatus. The 120 screw in this conveyer, as in conveyer 51, stops short of the opening in the conveyer pipe so that a portion of the steamed material fills such opening and practically seals the steamer against the entrance of air or 125 the escape of vapor.

130 At the same time that the material is being turned over and raked on the several shelves and gradually fed down through the steamer chamber 52, steam is admitted

near the base of the latter by way of pipe 57, such steam rising in a zigzag path in contact with the constantly changing surfaces of the body of material that passes 5 downwardly through the steamer as just described. Any excess of such steam, together with the vaporized solvent, escapes finally through a vapor pipe 58 which carries it to a condenser coil 59 in the tank 60. The 10 action of this opposing current of steam on the material is to thoroughly vaporize the solvent mixed with such material, so that substantially all such solvent is carried off with the steam to this condenser coil. From 15 the latter the condensed steam and solvent are conducted to a suitable separating device (not shown), or otherwise disposed of as seen fit.

In mentioning the excess of steam accompanying the solvent vapors, we wish to point 20 out the fact that the solvent vapor will be greatly in excess and that the steam is present only in small amount. The amount of steam present will actually be dependent upon whether the apparatus is being 25 forced or not. If it is being forced, the excess of steam will be great, whereas if it is being worked at a rate suitable to its capacity, the excess of steam will be quite 30 small.

The supply of steam to the steamer chamber by way of pipe 57 is controlled by a valve 63, which is in turn operated by means of a thermostat 64 mounted at a suitable 35 point in the wall of the chamber 52, so as to be in contact with the vapor within the latter. Inasmuch as the temperature of such vapor, consisting, as it does, of a mixture of steam and solvent, will vary, depending 40 upon the relative proportions of the two ingredients, it follows that there will be a gradual change of temperature within the steamer varying from bottom to top with the different proportions of steam and 45 solvent vapor, and that there will be some certain temperature which, if maintained at the selected point in the vapor space within the steamer chamber, will insure the practically complete absence of solvent or solvent 50 vapor at the base of the steamer. Accordingly, by properly locating the thermostat and adjusting its action, such thermostat may be adapted to automatically control the steam entering pipe 57, so as to 55 effect a practically complete recovery of the solvent in the material without the waste of steam.

By the foregoing automatically controlled steam-supply valve, we reduce the labor and 60 attention required in the case of the apparatus diagrammatically illustrated in Fig. 1, as well as secure more constant effects. As a further marked advantage, we should note that uneven working, involving either a 65 waste of steam, imperfect separation of vol-

atile, or both, due to irregularities in steam pressure available, irregularities of feed of material, or of composition thereof, is effectually avoided and uniform results obtained. In other words, complete separation 70 of volatile is obtained with a minimum of steam.

Other modes of applying the principle of our invention may be employed instead of the one explained, change being made as 75 regards the method herein disclosed, provided the step or steps stated by any one of the following claims or the equivalent of such stated step or steps be employed.

We therefore particularly point out and 80 distinctly claim as our invention:—

1. In a method of separating a volatile constituent from a material, the steps which consist in moving such material in contact with a counter current of steam, or the like, 85 whereby a mixture of steam and vaporized volatile is obtained in varying proportions at different points in the path of such current, and maintaining such mixture at a substantially constant temperature at some 90 selected point in such path intermediate between the ends thereof by regulating the supply of steam.

2. In a method of separating a volatile constituent from a material, the steps which 95 consist in moving such material in contact with a counter current of steam, or the like, whereby a mixture of steam and vaporized volatile is obtained in varying proportions at different points in the path of such current, and maintaining such mixture at a substantially constant temperature at some 100 selected point in such path intermediate between the ends thereof by automatically regulating the supply of steam by means 105 of a thermostatically controlled steam inlet valve, the sensitive element of the thermostat being placed at such selected point.

3. In a method of separating a volatile constituent from a material, the steps which 110 consist in moving such material in contact with a counter current of steam, whereby a mixture of steam and vaporized volatile is obtained in varying proportions at different points in the path of such current, and regulating the degree to which the volatile in the material is separated therefrom by maintaining such mixture of steam and vapor at substantially a constant temperature at a selected point in such current intermediate 115 between the ends thereof.

4. In a method of removing the residual solvent from an extracted material, the steps which consist in moving such material against a current of steam, and simultaneously stirring and turning over such material, the volume of steam being automatically regulated by the temperature of the mixture of steam and vaporized solvent resulting from the action of the steam on the 120 125 130

material at an intermediate point in the course of treatment.

5. In a method of removing the residual solvent from an extracted material, the steps
5 which consist in moving such material in contact with a counter current of steam, or the like, whereby a mixture of steam and vaporized solvent is obtained in varying proportions at different points in the path
10 of such current, and maintaining such mixture at a substantially constant temperature at some selected point in such path inter-

mediate between the ends thereof by automatically regulating the supply of steam by means of a thermostatically controlled steam 15 inlet valve, the sensitive element of the thermostat being placed at such selected point.

Signed by us, this 18 day of December, 1914.

EDWIN O. BARSTOW.
